UNITED STATES PATENT OFFICE

118,357

DESIGN FOR A TEXTILE FABRIC OR SIMILAR ARTICLE

Daniel A. Wechsler, New York, N. Y.

Application November 14, 1939, Serial No. 88,261

Term of patent 3½ years

To all whom it may concern:

Be it known that I, Daniel A. Wechsler, a citizen of the United States, residing in the city of New York, county of New York and State of New York, have invented a new, original, and ornamental Design for a Textile Fabric or Similar Article, of which the following is a specification, reference being had to the accompanying drawing, forming a part thereof.

The figure of the drawing is a plan view of a textile fabric or similar article, showing my new design.

I claim:

The ornamental design for a textile fabric or similar article, as shown.

DANIEL A. WECHSLER.
